[57] CLAIM

The ornamental design of a chair, substantially as shown and described.

DESCRIPTION

FIG. 1 is a front perspective view from above and one side of the chair, embodying my new design;

FIG. 2 is a rear perspective view from above and other side of the chair;

FIG. 3 is a front view of the chair;

FIG. 4 is a rear view of the chair;

FIG. 5 is a plan view of the chair;

FIG. 6 is an underneath plan view of the chair;

FIG. 7 is a side view of the chair;

FIG. 8 is a rear perspective view from below of the chair.

The chair is stackable and is intended for use in a kneeling-like sitting posture.

The chair has a frame, an upper supporting member to engage the posterior of the user and a lower supporting member to engage the shins of the user.
